His Attorney

UNITED STATES PATENT OFFICE

ARTHUR W. FISHER, OF FOREST HILLS BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF ELECTRIC LAMPS

Application filed July 7, 1927. Serial No. 203,965.

My invention relates to apparatus for the control of electric lamps, and particularly to lamps which are supplied with current from primary batteries.

I have found that when a battery, such as that of the caustic soda type, stands on open circuit for a considerable period of time, the battery develops an initial voltage that is considerably higher than the voltage after the flow of current has continued for a short time. When an electric lamp is supplied with voltage from a battery of this character and the circuit is so adjusted that the final or normal voltage of the battery is the correct voltage for the lamp, the initial voltage supplied to the lamp after the battery has been on open circuit for a considerable period of time tends to reduce the life of the lamp. One feature of my invention is the provision of means operating when the circuit for the lamp becomes closed to prevent the supply of excessive current to the lamp while the voltage of the battery is dropping to its normal value.

I will describe one form of apparatus embodying my invention, and will then point out the novel features thereof in claims.

The accompanying drawing is a diagrammatic view showing one form of apparatus embodying my invention.

Referring to the drawing, the reference character B designates a battery, the voltage of which rises above its normal value when the battery is on open circuit for a considerable period of time. This battery supplies current to an electric lamp L, through a circuit which includes a normally open contact 8 of a relay R. The circuit for the relay R, which circuit is designated by the reference character 2, may be controlled in any suitable manner; for example, relay R may be the well known approach lighting relay used in railway signaling systems of the type wherein the signal lamps are normally extinguished and become lighted upon the approach of a train.

The circuit for the lamp L also includes an operating winding 3 of a thermostat T having a normally closed contact 4 and a normally open contact 5. When the thermo-

stat T becomes energized by the supply of current to its operating winding 3, an interval of time elapses during which contact 4 remains closed, and after the expiration of such interval of time contact 4 opens and contact 5 closes. While contact 4 is closed, a relatively high resistance 6 is included in circuit with the lamp L, and when contact 5 is closed, a relatively low resistance 7 is included in circuit with the lamp L.

The operation of the apparatus is as follows: Assuming that contact 8 of relay R has been opened for a considerable period of time, contact 4 of thermostat T will be closed, so that when contact 8 closes, the relatively high resistance 6 will be included in series with the lamp L, and this resistance prevents the supply of an excessive amount of current to the lamp L while the voltage of battery B is dropping to its normal value. After the lapse of a period of time sufficient to enable the voltage of battery B to reach its normal value, contact 4 opens and contact 5 closes, thereby removing the high resistance 6 from the circuit of lamp L and inserting the low resistance 7 in this circuit. The high resistance 6 therefore prevents shortening of the life of the lamp L due to the excessive voltage developed by the battery B for a short period of time after the circuit for the lamp becomes closed at contact 8.

I have referred to the resistance 7 as having a relatively low value, but in some instances this resistance may have substantially zero value. The relation between the values of resistances 6 and 7 should be such that resistance 6 will cause current of normal value in the lamp L during the initial high voltage of battery B, and that resistance 7 will cause current of normal value in lamp L due to the normal or lower voltage of battery B.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a source of electric current the voltage of which rises above its normal value when on open circuit for a considerable period of time, an electric lamp, a normally open circuit including said source and said lamp, a slow acting thermostatic circuit controller having a winding included in said circuit, and means controlled by said circuit controller for preventing the supply of excessive current to said lamp when the circuit becomes closed and for subsequently reducing the resistance of the circuit.
- 15 2. In combination, a source of electric current the voltage of which rises above its normal value when on open circuit for a considerable period of time, an electric lamp, a normally open circuit including said source and said lamp, a thermostat included in said circuit, and means controlled by said thermostat for permitting the supply of normal current but preventing the supply of excessive current to said lamp after the circuit becomes closed and while the voltage of said source is dropping to its normal value.
- 30 3. In combination, a source of electric current the voltage of which rises above its normal value when on open circuit for a considerable period of time, an electric lamp, a thermostat having a winding and a normally closed contact and a normally open contact, a normally open circuit including said source and said lamp as well as said normally closed thermostat contact and a resistance, and an auxiliary circuit including said source and said lamp as well as the normally open contact of said thermostat but excluding said resistance.
- 35 40 4. In combination, a source of electric current the voltage of which rises above its normal value when on open circuit for a considerable period of time, an electric lamp, a normally open circuit including said source and said lamp, a thermostat having a winding included in said circuit, and means controlled by said thermostat for reducing the resistance of said circuit after the circuit has been closed long enough to allow the 45 50 voltage of said source to drop to its normal value.

In testimony whereof I affix my signature.
ARTHUR W. FISHER.
